DESIGN FOR A HAT

Murray Marks, New York, N. Y., assignor to Betmar Hats, Inc., New York, N. Y., a corporation of New York

Application April 2, 1938, Serial No. 76,250

Term of patent 3½ years

To all whom it may concern:

Be it known that I, Murray Marks, a citizen of the United States, with residence in the city and State of New York, and post office address at No. 55 West 39th Street, in the Borough of Manhattan, city and State of New York, have invented a new, original, and ornamental Design for a Hat, of which the following is a specification, reference being had to the accompanying drawing, forming part thereof, in which:

I claim:

The ornamental design for a hat, as shown.

MURRAY MARKS.
